LOGGING TRUCK AND TRAILER

Samuel Parks Newman, Sr., Acol, Tex.

Application June 13, 1940, Serial No. 340,387

6 Claims. (Cl. 280—145)

This invention relates to vehicle body construction and particularly to a bolster and bolster post, sometimes called a vehicle stake, for use in retaining loads of materials, such as logs, lumber, beams and the like, upon the vehicle. The general object of the invention is to provide such a bolster and bolster post combination in which the bolster post may be released and allowed to pivot outwardly and downwardly to a position below the horizontal so as to release and allow easy removal of the load from the vehicle without endangering the operator.

It is a further object of this invention to provide such a bolster post which may be readily applied to the usual bolster of a vehicle.

Another object of this invention is to provide such a bolster post and support therefor which will have sufficient strength to support and retain heavy loads, yet in which the support is of small dimensions and does not necessitate the use of special bolster construction.

Another object of this invention is to provide a means for positively locking a bolster post in its operative position.

Another object of this invention is to provide a bolster post of the character described in which the stresses exerted on the posts by the load will be transmitted more directly from the bolster post to the bolster, and in which the transmission of such stresses will not be dependent upon the strength of the means for securing the post mounting to the bolster.

Other objects and advantages of the invention will become apparent from the following description taken in connection with the accompanying drawing in which is set forth by way of illustration one embodiment of the invention.

In the drawing:

Fig. 1 is a side elevation of a bolster and bolster post carried thereby, with a portion of the bolster cut away and shown in longitudinal cross section for the purpose of illustrating the construction of the mounting for the bolster post;

Fig. 2 is a bottom plan view of the structure shown in Fig. 1;

Fig. 3 is an end elevation of the structure shown in Fig. 1;

Fig. 4 is a perspective view of the block by which the bolster post is mounted on the bolster;

Fig. 5 is a perspective view of the lower end of the bolster post showing the portion which receives the latching bolt for latching the bolster post in its upright or operative position;

Fig. 6 is a side elevation of a bolt which may

be employed for securing the bolster post extension in the clevis on the main bolster post.

The usual bolster employed in connection with trucks, trailers and similar vehicles for hauling logs, beams and the like is that of an H-beam having side flanges 1 and 2 and a web 3. This extends across the vehicle and the load is adapted to rest upon the upper edges of these H-beams or upon a flooring placed thereon as the case may require.

In accordance with this invention, a main vehicle stake or bolster post is mounted on each of the respective ends of the bolster as follows:

First, the web 3 of the H-beam forming the bolster is cut out for a short distance from each end. There is then placed between the sides 1 and 2 of the H-beam a block as shown in Fig. 4, said block having a pair of spaced bearing flanges or ears 4 and 5 parallel to but separated from each other and so disposed with respect to each other that they will just fit between the side flanges of the H-beam. Connecting these two bearing parts 4 and 5 together and extending between and integral with these bearing parts is a tongue-like part 6 which extends from the extreme outer surface of one bearing flange to the extreme outer surface of the other bearing flange. This tongue-like part 6 is adapted to fit under the end portion of the web beyond the part which is cut away, this being clearly illustrated in Fig. 1. The block is then preferably welded or otherwise rigidly secured to both the flanges and the web of the H-beam in the position shown in Fig. 1.

The bearing flanges 4 and 5, as above stated, are spaced apart and the lower end of the main vehicle stake or bolster post 7 is of a thickness to fit between these flanges. The flanges and the portion 7 of the bolster post are formed with holes 8, 9 and 10 respectively through which will be passed a pivot pin or bolt 11, thus pivotally mounting the bolster post on the bolster.

The bolster post may, if desired, be provided adjacent its upper end with a clevis 12 having an opening therethrough for slidably receiving the bolster post extension 13. This bolster post extension has openings 14 at spaced positions along its length for the purpose of receiving the removable pin or bolt 15 by which it is secured within the clevis 12. It will be noted that the pin 15 is provided with extension 16 which is pivoted at 17 to the body of the pin, so that when the pin is inserted and the part 16 is pivoted to a position at right angles to the main body of the pin, the pin cannot be withdrawn until the part 16 is

again moved into alignment with the main body of the pin, but it can then be readily withdrawn for the purpose of removing the bolster post extension 13.

At its lower end the bolster post is made of especially heavy cross section as illustrated and is provided adjacent the opening 10 with a notch 15a, which acts as a keeper to receive the sliding bolt 16a of the latching mechanism. This sliding bolt 16a extends through an opening 17 provided for the purpose in the tongue-like part 6 of the mounting block, and when the bolster post is in its upright position the bolt 16a may be moved toward the bolster post into the notch 15a to hold the bolster post in its upright position. It will further be appreciated that a force tending to move the bolster post down to a horizontal position will exert only a shearing force on the bolt 16a, and the stress will be transmitted directly through this shearing action on the bolt and through the tongue-like part 6 on the block to the web 3 of the H-beam. The transmission of this force will depend to a very small extent only upon the strength of the welding or other means of securing the mounting block in position on the H-beam.

The bolt 16a is adapted to be actuated by means of a lever 18 which extends through the slots 19 in the flanges of the H-beam beneath the web 3 and is pivotally mounted at 20 on a bracket 21 carried by one of the side flanges. This lever is connected to the bolt 16a, by means of links 22 so that when the lever 18 is swung about its pivot in one direction or the other the bolt will be moved longitudinally into or out of engagement with the slot 15a in the vehicle post.

In order that the lever 18 might be moved to release the vehicle post without danger to the operator, there is pivoted to the free end of this lever at 23 a rod 24, and the opposite end of this rod is pivoted at 25 to a lever 26 adjacent the remote end of the bolster, said lever being fulcrumed at 27 to a bracket 28 on the bolster. The lever 26 has a handle 29 which may be grasped to move the lever 26 and the linkage just described for the purpose of retracting the bolt 16 and releasing the bolster post. The bolt 16 is normally held in its engaged position by means of a spring 30 extending between a part of the rod 24 and a suitable means for attaching it to 50 the bolster.

From the foregoing it will be seen that a means has been provided for carrying out all of the objects of this invention, and that by the means provided a suitable bolster post may be secured to a customary type of vehicle bolster without the necessity for any special construction of the bolster or any additional bolster. It will further be seen that a means for mounting the bolster post on the bolster has been provided in which the stresses upon the bolster post will be transmitted directly to the bolster with the least possible stress transmitted through the welding or other parts securing the mounting to the bolster.

In addition to the foregoing, it will be appreciated that the construction illustrated may be secured in place without the necessity for a great deal of skill or any unusual or special tools, and that when secured in place it provides a means whereby the bolster post may be rigidly held in working position and yet may be released by an operator standing on the opposite side of the vehicle where he will be relatively safe from any injury.

Having described my invention, I claim:

1. In a device of the character described, in combination with a bolster, a mounting block carried by an end of said bolster, a bolster post pivotally secured in said mounting block for pivotal movement about a horizontal axis, and a latching bolt carried by a part of said mounting block and adapted to be moved in a horizontal plane, and when in its active position to engage a part of said bolster post to hold said bolster post in upright active position with respect to said mounting block and bolster, said part of said mounting block extending beneath and bearing directly against an under part of said bolster for transmitting the force from said bolster post through said bolt directly to the bolster.
2. In a mounting block for mounting a bolster post on a bolster, a bolster post, a unitary member having spaced substantially parallel bearing flanges adapted to receive an end portion of a bolster post between them, said flanges having aligned parts therein for providing a pivotal mounting for said bolster post therebetween, and a tongue integral with and connecting said flanges and adapted to extend beneath and to bear against an under part of the bolster to transmit forces from said bolster post to said bolster, said tongue having an opening therethrough adapted to provide a mounting for a bolt horizontally movable and directly engaging the said bolster post for latching said bolster post in a predetermined position with respect to the mounting block.
3. In a block for mounting a bolster post on a vehicle bolster, a bolster post and bearing parts adapted to provide a pivotal mounting for said bolster post, and a part extending laterally from said bearing parts and providing a sliding mounting for a bolt for directly engaging and latching said bolster post in a fixed predetermined position with respect to the block, said last mentioned part being adapted to bear against an under part of the vehicle bolster to transmit directly thereto the forces from said bolster post.
4. In a device of the character described, in combination with a bolster, a mounting block carried by an end of said bolster, a bolster post pivotally secured in said mounting block for pivotal movement about a horizontal axis and a latching bolt carried by a part of said mounting block and adapted to be moved in a horizontal plane and when in its extended position to engage a part of said bolster post to hold said bolster post in upright active position with respect to said mounting block and bolster, said part of said mounting block extending beneath and bearing directly against an under part of said bolster for transmitting the force from the said bolster post through the said bolt to said bolster, and means operable from a position adjacent the opposite end of the said bolster for moving said bolt from active to inactive position to release the said bolster post for downward swinging movement about its axis.
5. In a device of the character described, a mounting block for mounting a bolster post on a bolster, a bolster post and a unitary member having spaced substantially parallel bearing flanges adapted to receive an end portion of the bolster post between them, said flanges having aligned parts therein for providing a pivotal mounting for said bolster post therebetween, and a tongue integral with and connecting said flanges and adapted to extend beneath and bear against an under part of the said bolster to transmit forces

from said bolster post to said bolster, said tongue having an opening therethrough adapted to provide a mounting for a latching bolt, said bolster post at its lower end having a notched part cut therein to receive said latching bolt, and linkage means for moving said latching bolt through said tongue and into and out of active engagement with the said notched part of said bolster post.

6. In a device of the character described, a mounting block for mounting a bolster post on a bolster, a bolster post and a unitary member having spaced substantially parallel bearing flanges adapted to receive an end portion of the bolster post between them, said flanges having aligned parts therein for providing a pivotal mounting for said bolster post therebetween, and a tongue

integral with and connecting said flanges and adapted to extend beneath and bear against an under part of the said bolster to transmit forces from said bolster post to said bolster, said tongue having an opening therethrough adapted to provide a mounting for a latching bolt, said bolster post having at its lower end an enlarged and laterally extending part, said laterally extending part having a notch cut therein adapted to receive 5 said latching bolt when said bolster post is in its upright position, and means for moving said latching bolt through said tongue and into and out of active engagement with the said notched portion of the said enlarged and laterally extending lower part of the said bolster post.
